UNITED STATES PATENT OFFICE

118,903

DESIGN FOR A COMFORTABLE

Abraham J. Goldman, Brooklyn, N. Y.

Application December 16, 1939, Serial No. 88,934

Term of patent 3½ years

To all whom it may concern:

Be it known that I, Abraham J. Goldman, a citizen of the United States and resident of Brooklyn, New York, in the county of Kings and State of New York, have invented a new, original, and ornamental Design for a Comfortable, of which the following is a specification, reference being had to the accompanying drawing, forming a part thereof, and which is a plan view of a comfortable showing my new design.

I claim:

The ornamental design for a comfortable, substantially as shown.

ABRAHAM J. GOLDMAN.
